UNITED STATES PATENT OFFICE

150,347

DESIGN FOR A PICKUP ARM FOR ELECTRICAL PHONOGRAHS

Monte Ferar, Detroit, Mich., assignor to Colonial Radio Corporation, Buffalo, N. Y.

Application February 12, 1947, Serial No. 136,871

Term of patent 14 years

(Cl. D26—14)

To all whom it may concern:

Be it known that I, Monte Ferar, a citizen of the United States, residing at Detroit, in the county of Wayne and State of Michigan, have invented a new, original, and ornamental design for Pickup Arm for Electrical Phonographs, of which the following is a specification, reference being had to the accompanying drawing, forming part thereof.

In the drawing,

Fig. 1 is a perspective view of the pickup arm, Figs. 2 and 3 are respectively front and rear end views of the head and tail portions only of the arm, with the intermediate portion cut away,

Fig. 4 is a top plan view,

Fig. 5 is a side elevation, and

Fig. 6 is an enlarged fragmentary view of the pickup arm head showing the transparent outer covering in section.

The dash lines in the head portion represent

the inner housing of the pickup head visible through the transparent outer covering.

I claim:

The ornamental design for a pickup arm for electrical phonographs, as shown and described.

MONTE FERAR.
